UNITED STATES PATENT OFFICE.

OLLYN A. LAYNE, OF LOS ANGELES, CALIFORNIA.

TONGS.

Application filed May 24, 1924. Serial No. 715,523.

This invention relates generally to improvements in tongs, and more particularly has to do with tongs of the chain type wherein the work, usually in the form of a pipe, 5 is embraced by a chain fixed to the tongs handle at one end and releasably attached to the handle at the other end.

The invention is applicable to various types of chain wrenches or tongs but may be 10 applied with special advantage to so called "back-up tongs" for making and breaking joints of well pipe or drill stem during drilling operations with a rotary rig. During 15 wrenching operation, the jaw teeth of such tongs are caused to bite deeply into the work, and the chain is placed under great tension and drawn very tightly about the pipe. The handle, being backed up against a stationary abutment, cannot be conveniently 20 moved back to release the tongs. As a result, it is extremely difficult to release the wrench from the work when the usual latch between handle and chain is employed as a 25 releasable connection therebetween. The lost time, abused and battered wrenches, and 30 general unsatisfactory results emanating from these conditions are well known to those acquainted with the art.

Therefore it is among the objects of my 35 invention to provide tongs having a latch which may be manipulated with ease and speed, both in applying and releasing the wrench.

I am aware it is old in the art to provide 40 a latch lever pivoted to the free end of the chain and adapted to be cammed behind a hook on the tongs handle in order to tension the chain and draw it snugly around the work. My device differs from this general 45 type of wrench in that the latch lever is not actuated to tension the chain but merely forms a releasable connection between 50 tongs handle and chain. The chain is of a length to allow the latch to be freely 55 moved behind the hook—in fact it may be actually spaced from the engagement face of the hook—when the tongs handle is thrust 60 forwardly towards the work and the chain loosely drawn about the work. The initial 65 tensioning of the chain is accomplished by 70 subsequent longitudinal movement of the tongs away from the work which movement 75 first causes locking engagement between the

latch and tongs handle and then takes up 55 the chain slack and carries the jaw into operative position and engagement with the work.

Thus, no heavy pressure need be exerted 60 on my latch in order to rotate it into locking position, and the latch and its mounting are not subjected to those strains incident 65 to the actuation of the usual cam lever latch. Worn chain links in no way affect the efficiency of my latch, for the additional slack existing in the chain by reason of wear, 70 is taken up by merely moving the tongs handle back further than normal. On the other hand, a latch of the type utilized for tensioning the chain, does not operate efficiently 75 after the chain links or link pins wear or stretch sufficiently to increase the overall length of the chain, for the cam action is designed to take up only a predetermined amount of chain slack, and when the amount 80 of slack increases over normal, the latch is no longer competent to place the chain under desirable tension.

The latch levers of wrenches which depend 85 upon cam action for tensioning the chain must necessarily be of considerable length 90 in order that the leverage may be ample to enable the operator to tension the chain sufficiently to allow the latch nose to cam 95 into its seat. As a result, such levers are comparatively cumbersome and bulky and a wrench equipped therewith may not be used in cramped quarters. Furthermore, the operator must cam the latch into place after the chain encircles the work, and where the working space is restricted, this separate and delayed latch movement is often impossible of accomplishment, especially since it requires considerable effort, applied in a 100 particular manner, to effect chain take-up by latch movement.

The fundamental characteristics of my wrench enable me to employ a relatively 105 small latch handle which occupies a minimum of space and is movable into locking position before the chain is applied to the work. Consequently no manual actuation 110 of the latch is required in tensioning the chain and the wrench may be applied to work which is inaccessible to other wrenches.

My latch is also "self-locking," that is, 115 when it is in locking engagement with the

tongs handle, no auxiliary member need be employed to retain the latch in such engagement. Yet the chain need not be further tensioned to an appreciable extent when the latch is rotated to release position.

I will point out further novel features and objects of the invention in the following detailed description, reference being had to the accompanying drawings, in which—

Fig. 1 is a top plan view of a wrench constructed in accordance with my invention and showing the chain drawn about a pipe but not under tension;

Fig. 2 is an enlarged fragmentary view similar to Fig. 1, but shown partly in section and illustrating the parts in the position they assume when the chain is tensioned about the work;

Fig. 3 is a side view of the wrench in application on the work; and

Fig. 4 is a section on line 4—4 of Fig. 2.

At the outset, I wish to make the reservation that while I have illustrated and will describe a wrench which is of full efficiency only in its application to work of or close to a given diameter, the invention, in its broader aspects, is also adaptable to adjustable wrenches, and I wish to reserve for myself all applications of the invention as fall within the scope of the broader claims appended hereto.

Referring to the drawings, numeral 10 indicates a wrench handle which preferably, though not necessarily, is integral with body member 11. A pin 12 (Fig. 4) removably secures the arcuate die or toothed jaw 13 to one side of member 11, while a stop or abutment 14, preferably slightly hooked at its outer end, is provided on the opposite side of member 11. The end link 15 of chain 16 is pivotally connected to member 11, while pivotally connected by pin 18 to link 17 is an attachment link 19, which may be considered as an end link of the chain.

A latch lever 20 is pivoted to link 19 at 21 and is preferably in the nature of a bell-crank, one arm 22 of which is in the form of a locking nose, and the other arm 23 forming the latch handle. Attachment link 19 includes the spaced side arms 24 (preferably doubled for strength) and the bridge piece or stop 25 spanning the space between said arms. Nose 22 is adapted to swing between arms 24 when lever 20 is rotated about pin 21, but clockwise rotation of the lever, as viewed in Figure 2, is limited by reason of stop 25 extending into the path of handle 23, while nose 22 is adapted to engage said stop to limit the counter-clockwise rotation of said lever.

Since stop 25 extends into the included angle between the nose and handle, it functions to prevent the lever from swinging to such a position as would bring handle 23 into axial parallelism with links 19; and

therefore said handle always projects laterally from the link and is always in a position to be readily and fully grasped, whether or not the chain be drawn about the work (pipe P, for instance) and whether or not the latch be in locking engagement with member 11.

It will also be noted that when crank 20 is in the full line position of Figure 2 (which I will hereinafter designate as the "locking position" whether or not the latch be in engagement with member 11 or abutment 14) the nose center C lies at one side of the axial plane (indicated at A in Fig. 2) common to pins 18 and 21.

When the wrench is to be applied to pipe P, member 11 is thrust forwardly towards the work to bring the effective teeth of the jaw past the center of the pipe, as illustrated in Figure 1. This initial position of the jaw may also be described thus: Such teeth of the jaw as are later to be brought into operative engagement with the work are now beyond axial plane B of the work, which plane is substantially perpendicular to the longitudinal axis of the jaw. Handle 23 is then grasped and moved in a manner to draw the chain about the work. If the latch is not in locking position this single movement not only draws the chain about the work but also moves the latch to locking position. The chain being of sufficient length to allow the lever (in its locking position) to be brought into engagement with member 11 at a sufficient distance to the rear of abutment 14 to leave clearance between said abutment and nose 22, the latch is easily placed in that position, as illustrated in full lines in Figure 1, by a continuation of the single movement. The nose is now in "locking position" and is bearing on member 11, but is not yet in "locking engagement" with abutment 14.

It is a noteworthy feature of the invention that by reason of the particular form and arrangement of the wrench elements, the operator is able to swing the chain about the work and position the locking nose in proper alignment with member 14 by one continuous sweeping movement of his arm and without appreciably tensioning the chain. This is in contradistinction to the cam lever type of latch, where one movement draws the chain about the work, and a separate and independent movement of the latch is required to move said latch into locking position, said independent movement being accomplished only by the expenditure of considerable effort as it is accompanied by a tensioning of the chain.

By reason of the latch normally being in full locking position (and when not in this position, being movable thereinto by the same movement which draws the chain about the work) it is possible to apply the

wrench in minimum time, a very important feature in certain situations, notably in the making and breaking of drill stem tool joints.

Considering the time required for wrench application, my device is superior to ordinary chain tongs where the link pins at the free end of the chain are hooked over lugs on the handle. To explain, while there is only one efficient point of attachment between chain and handle, the link pins provide a plurality of attachment combinations, and often the operator must try several of these combinations before he strikes the particular one suitable to the work in hand. This "juggling" involves loss of time and is most aggravating. On the other hand, it is self-evident from the foregoing description that the application of my wrench to work involves no such "fitting and trying," for the latch may be brought into initial contact with the side face of member 11 at any point, between obvious limits, and that subsequent longitudinal movement of handle 10 effects a lock between chain and handle irrespective of the location of said point of initial contact. In other words there is no necessity for the fine adjustment of any of the wrench parts during application to work.

The grip on handle 23 may then be released, and member 11 (handle 10) is drawn back until abutment 14 engages nose 22, the nose then being both in "locking position" and "locking engagement" with member 11.

I have differentiated between "locking position" and "locking engagement" in order to aid in the interpretation of certain claims appended hereto. The chain is of such effective length that when locking engagement occurs, as illustrated by full lines in Fig. 2, the effective teeth of the jaw come into operative engagement with the work, and further withdrawal of member 11 tensions the chain about the work and subsequent working pressure on handle 10 causes the jaw teeth to bite farther into and grip the surface of the work. Thereafter the wrench may be actuated to turn pipe P, or may be utilized to hold said pipe stationary while work is being performed thereon.

Under ideal conditions, the length of the chain 16 is such that locking engagement of abutment and nose occurs simultaneously with the operative engagement of the center teeth of die 13 with the periphery of the work. Of course, it is not essential to the successful operation of the wrench that the center teeth be those engaged, and ordinarily ideal conditions are not met with, by reason of manufacturers' variations in outside diameters of standard pipes, and slack developing in the chain due to linkage wear will cause other than the center jaw teeth to engage the work; but such conditions, within reasonable limits, do not detract from the

efficiency of the wrench as it may be actuated when any of the teeth are in operative engagement with the work.

As before noted, center C of nose 22 is off-center with relation to pivots 18 and 21 when the latch is in "locking position," and since abutment 14 is in alignment with center C and since said center lies at that side of plane A which is remote from member 11 and work P, the pull of the chain under tension does not tend to release the nose from abutment 14, but rather tends to seat the nose more firmly. Therefore no keeper or other auxiliary means is necessary to retain the latch in locking engagement, and the latch may be properly called "self locking."

In order that the pull exerted on link 19 by the tensioned chain may not cause said link to fulcrum on member 11 at any point intermediate the link pivot 18 and nose center C, and thereby tend to rotate said link and crank out of locking position, body member 11 and links 19 are so formed and arranged that arms 24 are clear of member 11 throughout their extent, or at least from pin 18 to center C, projected. Thus, while the relatively broad nose 26 of member 11 engages link 17, arms 24 are spaced apart sufficiently to clear the sides of the relatively thin web 27. This feature of construction is illustrated in Figures 2 and 4.

The central washer 18^a on pin 18 (or, in effect, the pivoted end of the attachment link 19) bears against member 11 about where web 27 merges into nose 26. This engagement establishes the position of the pivoted end of link 19 irrespective of the diameter of the work and in spite of the tendency of the tensioned chain to move said pivoted ends towards the work. Thus, since the relative position of link 19, lever 20 and abutment 14 are always the same when the latch is in locking engagement, the degrees of off center lock and the latch movement into and out of locking engagement are constant in all situations. Were pin 18 free to clear nose 26 during application of the wrench, the degree of angularity between link 19 and member 11 would vary with work of different diameters, and this would result in an undesired variable locking effect.

Since handle 23 is not required to extend along and in engagement with the side face of member 11 when the latch is locked in engagement with said member, the accumulation of foreign matter on said side face at points opposite the handle will not interfere with the retention of the nose in its correct alignment with abutment 14 when said nose first engages member 11 and will not prevent said nose from assuming its position of "self-lock."

When it is desired to release the wrench from the work, latch 20 is rotated to the

dotted line position of Figure 2, nose 22 fulcruming behind hook 14 and on the side of member 11, and link 19 moving outwardly about pin 18 as a center during such rotation. As pin 21 moves outwardly from member 11, and hence out of alinement with abutment 14, the tension of the chain is released so said chain may be easily removed from the work.

10 It will be noted that while the latch is self-locking, the tension of the chain need not be appreciably increased during the release movement of the latch, and that during rotation of the latch, nose 22 is moved 15 longitudinally from beneath the overhang or hook end of abutment 14 so the nose may be cleared from the abutment, pin 21 moved out of alinement with the abutment, and chain 16 slackened away before said nose 20 leaves its engagement with the side face of body 11; and practically the only resistance to this movement is the sliding friction between the nose and the side face of member 11, a resistance overcome with but little 25 effort. This manner of release is superior to those common to other wrenches in that release movement of my latch is under control of the operator, and when handle 23 is 30 grasped by the operator's hand during release rotation thereof the latch may be held from suddenly snapping off the abutment and causing the heavy chain to whip away from the work if desired.

However, when used in connection with 35 rotary rigs, it is most important that the wrench release be accomplished with great speed. A single hammer tap against handle 23 suffices to move nose 22 out of locking engagement with abutment 14, whereupon the 40 chain whips lever 20 clear of said abutment and the chain unwraps itself from the work. This movement is caused mainly by the outward impetus given link 19 (away from body 11) by the chain tension and by the 45 fact that, at the instant the chain tension is being released, the nose 22 is moving in such a direction as to cause the chain strain to quickly throw the latch end of link 19 outwardly. The impetus thus given the chain 50 is sufficient to throw it entirely away from abutment 14.

While I have illustrated and described a preferred embodiment of my invention, I do not wish to be limited thereto except for such 55 limitations as a fair interpretation of the appended claims may import.

Having described a preferred form of my invention, I claim:

1. A wrench embodying a body member, 60 a jaw, a chain connected at one end with the member, a locking lever connected to and carried by the other end of the chain and adapted to be moved into and out of locking position and into and out of locking engagement with the member, the lever being

adapted to provide a handle for drawing the chain about given work before said lever is in engagement with the member, and coacting means on the lever and chain adapted to maintain the lever in locking position during such movement of the chain about said work.

2. In a pipe wrench, a body member, a jaw, a chain connected at one end with the member, a locking lever pivotally connected with the other end of the chain and adapted to be swung into and out of locking position, and means adapted to establish the locking position of the lever, said means comprising a stop on the chain adapted to coact with the lever and limit its pivotal movement.

3. In a pipe wrench, a body member, a jaw, a chain connected at one end with the member, a bell-crank pivoted to a chain link near the other end of the chain, a locking nose on one arm of the crank, a handle on the other arm of the crank, said nose being adapted to be moved to and from engagement with the member, the crank being positioned on the chain so the longitudinal axis of said handle extends angularly with respect to the longitudinal axis of said chain link, and means on the chain adapted to limit the pivotal movement of the crank and prevent said handle from being moved into axial parallelism with said link.

4. In a pipe wrench, a body member, a chain fixed at one end to said member, a releasable connection between said member and the opposite end of said chain, and a jaw adapted to be brought into operative engagement with given work by longitudinal movement of the handle and a consequent tensioning of the chain after the chain embraces the work and is releasably connected to said member, said releasable connection including a one-piece lever on and independently movable with respect to said chain, said lever being adapted to be brought into locking engagement with said member by said longitudinal movement, and the lever and member being so associated that they remain, unassisted, in locking engagement until the lever is independently moved.

5. The combination with the handle, jaw and chain of a pipe wrench, a lever pivotally connected with a link of the chain, an abutment on the handle, and a locking nose on the lever and adapted to engage behind the abutment for releasably attaching said link to the handle, the abutment and nose being so associated when in engagement that the nose center lies without the line of centers of the pivotal mounting of the lever and the pivotal connection between said link and the adjacent link of the chain and at that side of said line of centers which is remote from the handle.

6. The combination with the handle, jaw

and chain of a pipe wrench, a lever pivotally connected to one end of a chain link, an abutment on the handle, and a locking nose on the lever and adapted to engage 5 behind the abutment for releasably attaching said link to the handle, the other end only of said link being adapted to bear on said handle when the link and handle are in attachment, and the abutment and nose 10 being so associated when in engagement that the nose center lies without the line of cen-

ters of the pivotal mounting of the lever and the pivotal connection between said link and the adjacent link of the chain and at that side of said line of centers which is remote 15 from the handle.

In witness that I claim the foregoing I have hereunto subscribed my name this 14th day of May 1924.

OLLYN A. LAYNE.
